CLAIM

(51) **LOC (14) Cl.** **06-01**

The ornamental design for a safety seat with anchor, as
shown and described.

(52) **U.S. Cl.**

DESCRIPTION

USPC **D6/333**

FIG. 1 is a front, right, and top perspective view of the first
embodiment of the safety seat with anchor in an extended
position showing our new design;

(58) **Field of Classification Search**

FIG. 2 is a front, left, and top perspective view thereof;

USPC D6/334-336, 338-339, 333, 716,

FIG. 3 is a front view thereof;

D6/716.1-716.7; D12/129; D21/412,

FIG. 4 is a rear view thereof;

D21/419; 280/30-31

FIG. 5 is a left view thereof;

CPC A47D 13/02; A47D 13/10; A47D 1/00;

FIG. 6 is a right view thereof;

A47D 1/002; A47D 1/004; B60N 2/22;

FIG. 7 is a top view thereof;

B60N 2/24; A47C 7/021; A47C 7/022;

FIG. 8 is a bottom view thereof;

A47C 7/002; A47C 7/18; A47C 7/24;

FIG. 9 is a front, right, and top perspective view of the
second embodiment of the safety seat with anchor in an

A47C 3/00; A47C 3/02; A47C 3/025;

retracted position showing our new design;

A47C 3/20;

FIG. 10 is a front, left, and top perspective view thereof;

(Continued)

FIG. 11 is a front view thereof;

FIG. 12 is a rear view thereof;

FIG. 13 is a left view thereof;

FIG. 14 is a right view thereof;

FIG. 15 is a top view thereof; and,

FIG. 16 is a bottom view thereof.
